US00D671509S

(12) **United States Design Patent**
Moriguchi et al.

(10) **Patent No.:** US D671,509 S
(45) **Date of Patent:** ** Nov. 27, 2012

(54) **LIGHT EMITTING DIODE MODULE**

(75) Inventors: **Takashi Moriguchi**, Kyoto (JP);
Masahiko Kobayakawa, Kyoto (JP)

(73) Assignee: **Rohm Co., Ltd.**, Kyoto (JP)

(**) Term: **14 Years**

(21) Appl. No.: **29/408,953**

(22) Filed: **Dec. 19, 2011**

(30) **Foreign Application Priority Data**

Jul. 22, 2011 (JP) 2011-016883

(51) **LOC (9) Cl.** 13-03

(52) **U.S. Cl.** D13/180

(57) **CLAIM**

We claim the ornamental design for a light emitting diode module, as shown.

DESCRIPTION

FIG. 1 is a perspective view of a light emitting diode module according to our new design;

FIG. 2 is a front view of the same module;

FIG. 3 is a rear view of the same module;

FIG. 4 is a top plan view of the same module;

FIG. 5 is a bottom view of the same module;

FIG. 6 is a right side view of the same module; and

FIG. 7 is a left side view of the same module; and,

FIG. 8 is a sectional view of the same module taken along lines 8-8 in FIG. 4.
